CRANSTON H. CARPENTER, OF IRWIN, PENNSYLVANIA, ASSIGNOR TO WESTINGHOUSE ELECTRIC & MANUFACTURING COMPANY, A CORPORATION OF PENNSYLVANIA.

THREE-PHASE CRUCIBLE FURNACE.

1,415,989.

Specification of Letters Patent. Patented May 16, 1922.

Application filed May 22, 1920. Serial No. 383,378.

To all whom it may concern:

Be it known that I, CRANSTON H. CARPENTER, a citizen of the United States, and a resident of Irwin, in the county of Westmoreland and State of Pennsylvania, have invented a new and useful Improvement in Three-Phase Crucible Furnaces, of which the following is a specification.

My invention relates to electric furnaces and particularly to electric-resistance melting furnaces and it has for one of its objects to provide a furnace which shall have an improved resistor comprising a refractory material to be placed in close operative engagement with the material container and which shall have improved means for conducting current to and from the resistor and be so designed that it may be used on either single or polyphase alternating-current supply circuits, with relatively small changes in its construction.

More specifically, my invention embodies a tiltable container in which a suitable melting crucible is located. A plurality of refractory resistance elements surround the crucible and a plurality of wells or hoppers, filled with a mass of granular electrical conducting material operatively engaging the resistors, are symmetrically disposed around the resistor. At or near the bottom of each of the wells is a suitable terminal electrode made of carbonaceous material to which the electric supply conductors may be connected. A suitable cover member for the furnace may also be provided.

Referring to the single sheet of drawings, Figure 1 is a cross-sectional view of the device embodying my invention, on the line I—I of Fig. 2, and Fig. 2 is a vertical cross-sectional view of the same device taken on the line II—II of Fig. 1.

The supporting structure of the furnace comprises an exterior metal casing 1 which encloses an outer shell 2 of heat-insulating brick and an inner shell 3 of fire-clay brick. The walls of the inner shell 3 are so spaced apart as to provide a substantially cylindrical chamber 4 in which may be placed a crucible 5 to receive the material to be melted. As the melting crucible is commonly made cylindrical in contour, it is usual to make the rest of the structure of the furnace of the same general contour and I have, therefore, shown the cross-section of the fur-

nace as circular in shape, although this is not necessary.

A plurality of wells or hoppers 6 are provided in the outer shell 2 and the inner shell 3, and are so disposed as to be in contact with the cylindrical chamber 4. The number of wells or hoppers is selected in accordance with the number of supply-circuit conductors which, of course, depends upon the number of phases of the alternating-current supply circuit, and they are to be symmetrically located around the periphery of the crucible 5.

Provision is made in the inner shell 3 for a plurality of substantially horizontal chambers 7 in which are placed angularly-extending refractory resistance members 8 which may be made of carborundum or of silicon carbide. As shown in Fig. 1, each of the resistor members 8 covers substantially one-third of the periphery of the crucible 5 and is, therefore, adapted to operate on a three-phase supply circuit.

At or near the bottom of each of the hoppers 6 is placed a solid carbonaceous terminal electrode 9 to which a corresponding supply-circuit conductor 10 may be suitably connected. A mass of granular electrical-conducting material 11, such as graphite or coke, is placed in each of the hoppers 6 and may be suitably tamped therein to conduct the current from the terminal electrode 9 to and from the ends of the resistor members 8. As a small space is provided between the adjacent ends of each of the resistor members 8, they may expand, during operation, without danger of fracture. As shown in Fig. 2, I provide a plurality of resistor members 8 located one above another and I desire it to be understood that any suitable or desirable number of such resistors may be employed in parallel, the object being, of course, to heat the crucible as uniformly as possible, thus preventing overheating of any part thereof.

Suitable supporting pedestals 12 are provided which co-operate with short suspension members 13 suitably attached to the metal casing 1 to permit of the furnace being tilted and of pouring out the metal through a pouring spout (not shown) provided in the body of the furnace. A cover member 14, having a charging door 15, is provided at the top of the furnace to prevent

excessive loss of heat from the furnace while the same is in operation.

Where the refractory resistor members, such as carborundum, are used, it is difficult to provide suitable means for conducting the current to and from such resistors, and, as it is highly desirable to use terminal electrodes to which the supply-circuit conductors may be connected, it becomes necessary to provide current-conducting means therebetween which will permit substantially continuous operation of the furnace at relatively high temperatures. If the terminal electrode is directly connected to the resistor, oxidation of either or both will take place during the operation of the furnace, resulting in a poor contact therebetween and necessitating frequent attention thereto. The use of finely divided granular material, such as graphite or coke, which may be thoroughly tamped in place, provides a large number of current-conducting paths through the resistor and, if any oxidation of either the resistor or the granular material takes place, it may be retamped and may be easily and quickly removed and replaced whenever this becomes necessary after a relatively long period of operation of the furnace.

It will be noted that I provide a new and improved form of refractory resistor which may be located in close operative contact with the material container and that I provide new means for conducting the current from the terminal electrode to the resistor proper.

Various modifications may be made in the device embodying my invention without departing from the spirit and scope thereof, and I desire that only such limitations shall be placed thereon as are imposed by the prior art or are specifically set forth in the appended claims.

I claim as my invention:

1. In an electric furnace, the combination with a container, of a resistor surrounding said container, a plurality of wells symmetrically disposed around said container, granular electrical-conducting material contained in said wells and operatively engaging said resistor, and terminal electrodes in said wells adapted to connect said resistor to a source of electromotive force.

2. In an electric furnace, the combination with a container, of a resistor adjacent said container comprising solid refractory electrical-conducting material, a plurality of wells symmetrically disposed around said container, electrodes in said wells adapted to be connected to a source of electromotive force, and a mass of granular electrical-conducting material interposed between each of the electrodes and the resistor.

3. In an electric furnace, the combination with a container, of a resistor adjacent said

container comprising solid refractory electrical conducting material, a plurality of hoppers adjacent to, and symmetrically disposed around, said container, electrodes in said hoppers adapted to be connected to a source of electromotive force, and a mass of granular electrical-conducting material interposed between each of the electrodes and the resistor.

4. In an electric furnace, the combination with a container and means for tilting the container, of a resistor adjacent to, and surrounding, said container and comprising blocks of refractory electrical-conducting material, a plurality of hoppers adjacent to, and symmetrically disposed around, said container, electrodes in said hoppers adapted to be connected to a source of electromotive force, and a mass of granular electrical-conducting material interposed between each of the electrodes and the resistor.

5. In an electric furnace, the combination with a container having an open end and means for tilting the container, of a resistor adjacent to, and surrounding, said container and comprising solid refractory electrical-conducting material, a plurality of hoppers adjacent to, and symmetrically disposed around, said container, electrodes in said hoppers adapted to be connected to a source of electromotive force, a mass of granular electrical-conducting material interposed between each of the electrodes and the resistor, and heat-insulating means entirely surrounding said container.

6. In an electric furnace, the combination with a refractory heat-insulating casing, a crucible in said casing, and means for tilting said casing, of a resistor in said casing adjacent said crucible, a plurality of hoppers adjacent to, and symmetrically disposed around, said crucible, electrodes in said hoppers, a mass of granular electrical-conducting material in said hoppers interposed between said electrodes and said resistor, and covering means for said casing and said crucible.

7. In an electric furnace, the combination with a crucible, of a resistor disposed adjacent to said crucible and comprising solid refractory electrical-conducting material, a plurality of wells symmetrically disposed around said crucible, solid carbonaceous electrodes contained in said wells and adapted to be connected to a source of polyphase electromotive force, and a mass of granular electrical-conducting material interposed between each of the electrodes and the resistor.

8. In an electric-resistance furnace, the combination with a crucible, of a resistor surrounding said crucible and comprising blocks of solid refractory electrical-conducting material, three wells symmetrically disposed around said crucible, solid carbonaceous electrodes contained in said wells and

adapted to be connected to a source of three-phase electromotive force, and a mass of granular electrical-conducting material interposed between each of the electrodes and the resistor.

9. In an electric-resistance furnace, the combination with a container, of a resistor encircling said container and consisting of a plurality of blocks of refractory electrical-conducting material of arcuate form, the angular extent of each block being determined in accordance with the number of phases of the supply circuit.

10. In an electric-resistance furnace, the combination with a container, of a resistor 15 encircling said container and comprising a plurality of blocks of silicon carbide of arcuate form, the angular extent of each block being determined in accordance with the number of phases of the electrical supply 20 circuit.

In testimony whereof, I have hereunto subscribed my name this 17th day of May, 1920.

CRANSTON H. CARPENTER.
